RADIO SYSTEM FOR TRANSMISSION AND
RECEPTION ON THE SAME FREQUENCYMelvin L. Doelz, Cedar Rapids, Iowa, assignor to
Collins Radio Company, a corporation of Iowa

Application February 28, 1944, Serial No. 524,206

9 Claims. (Cl. 250—13)

1

This invention relates to a transmitter-receiver combination, and more particularly to a radio system ensuring transmission and reception on the same frequency.

One feature of this invention is that it provides an improved radio transmitting and receiving combination system; another feature of this invention is that a single tuning means effects coordinated selection of a desired frequency in both the transmitting and receiving portions of the system; still another feature of this invention is that transmission and reception take place on the same frequency despite any variation of the tunable oscillator from its calibrated frequencies; yet another feature of this invention is that the system is readily tunable to any desired frequency in any of a plurality of frequency ranges; a further feature of this invention is that frequency drift is reduced; still a further feature is that undesired harmonics in a mixer output are minimized; and yet a further feature of this invention is that it provides similar frequency spread on each of a plurality of bands and direct frequency reading on any such band. Other features and advantages of this invention will be apparent from the following specification and the drawings, in which:

Figure 1 is a block diagram of a system embodying my invention; Figure 2, comprising the portions 2a and 2b, is a circuit diagram of an operable embodiment of a transmitter-receiver combination system corresponding to the diagram of Figure 1; and Figure 3 is a detail view of a frequency indicating arrangement which may be used with this system.

Two-way radio combination is becoming of increasing importance, and under many circumstances it is desirable to have the transmitting and receiving equipment tunable over a desired frequency range, or a plurality of frequency ranges. Under such conditions the transmitted frequency cannot be crystal controlled, but must have a frequency controlled by a tunable oscillator tank circuit. Despite the greatest care in design and construction, an oscillator tank circuit undergoes frequency changes as the result of its exposure to variations in temperature, humidity, etc., and this makes it difficult to determine accurately, by any system of dial calibration, the frequency being transmitted or received, particularly in the higher frequency bands, as those used in aircraft work.

I have devised and am here disclosing a single-control (in so far as tuning is concerned) radio transmitting and receiving combination system

2

wherein transmission and reception on the same frequency are ensured. This enables an operator to tune in on another station which is transmitting, and then to go on the air himself as soon as the other station ceases transmission with full assurance that his signal is on the same frequency as that on which the other station was transmitting, regardless of the setting of his tuning dial or the accuracy of its calibration. The system which I am here disclosing and claiming makes use of a variable generator or tunable oscillator and of a fixed frequency generator comprising a source of a plurality of fixed frequencies, both generators being operative whenever the system is in operation and their outputs being mixed. In one case the mixed output is amplified and transmitted; in the other case, in order to receive on the same frequency, the fixed frequency generator has its frequency displaced and the resultant displaced output is used as the local or heterodyning wave of a super-heterodyne receiver having its intermediate frequency amplifier tuned to a frequency representing the difference between the initial and displaced frequencies of the mixer output.

The system which I am here disclosing and claiming is only one system capable of ensuring transmission and reception on the same frequency provided the tunable oscillator is left at the same setting. Another system for accomplishing this purpose, and broader claims thereto, are to be found in a copending application of one Frank M. Davis, Serial No. 548,978, filed August 11, 1944. Still other systems for transmitting and receiving on the same frequency with a single-control arrangement are the subject matter of a copending application of one Arthur A. Collins, Serial No. 524,204, filed February 28, 1944, now Patent No. 2,447,490, which issued August 24, 1948, and of another application of the said Frank M. Davis, Serial No. 524,205, filed February 28, 1944, which has matured into Patent No. 2,402,606, dated June 25, 1946, and of an application of Frank M. Davis, filed July 24, 1946, as Serial No. 685,934.

My system shown and claimed here comprises, as one of its principal elements, means for providing a wave output which consists of a fixed frequency generator here shown as comprising a one megacycle oscillator and a multiplier for providing any desired multiplication of such frequency; a variable generator or tunable oscillator tunable over a band having a frequency width equal to the spacing between the various fixed frequencies; and a mixer for mixing the outputs of these two generators. Transmission is effected

by amplifying and transmitting such wave output, using a certain fixed frequency and any desired frequency within the range of the tunable oscillator. Reception is effected by displacing the fixed oscillator frequency to another fixed frequency adjacent to that used in transmission, the resultant mixed wave output thus being displaced by a known frequency, the displaced wave output being used as a local heterodyning wave in a super-heterodyning receiver. When one has tuned to another signal, switching to transmission ensures sending on the exact frequency of the signal previously heard; and conversely, when one has been transmitting, switching to receiving without touching the tuning control ensures reception on the exact frequency being previously transmitted.

While I am terming the system disclosed here a "single-control system," it will be understood that by this it is meant that there would be only a single tuning control for both the transmitting and receiving portions of the system, which would normally be housed in a single cabinet. In addition, of course, there would be a band switch, antenna coupling and loading controls (at least in high frequency work), an on-off switch or several of such switches, and a volume control for the receiving system. The switch-over from transmission to reception, and vice versa, would normally be effected by a keying relay, or by a push-button-operated relay associated with the microphone of the transmitter. With a system of this kind, no matter how inexperienced the operator may be, once he finds and hears a given station (whether it be another airplane, a ground station, or the like) he is sure to be able to talk to it, sure to be on that frequency merely by effecting the switch-over from reception to transmission. Another advantage, claimed in one of the aforesaid copending Davis applications (Serial No. 548,978, filed August 11, 1944), is that the same antenna tuning and loading circuit may be used for coupling both the transmitter and receiver to the antenna, so that the antenna can be tuned during reception, without breaking radio silence, with assurance that transmission will be at or very near maximum power without the necessity for adjustment of the antenna tuning and loading controls after transmission has been started.

In the particular embodiment of my system illustrated here and referring first more particularly to the block diagram (Figure 1) a tunable oscillator A delivers its output to a mixer B, this mixer also having supplied thereto any of various predetermined fixed frequencies here shown as generated by a fixed oscillator C and a multiplier D. The wave output of the mixer B is passed through a buffer amplifier E and a tunable filter circuit F, the output of this tunable filter circuit being connected to the movable element of a two-position switch F'. This is one of a gang of switches effecting switch-over from transmission to reception, the position of the movable switch element shown in solid lines connecting the filter circuit to the receiving system to deliver the wave output thereto, the connection in the other or transmitting position (shown in dotted lines) connecting the filter circuit to the power amplifier. During transmission the wave output of the mixer B serves as a carrier frequency and is amplified in the power amplifier H, desired modulation being effected by a modulator G. Any conventional form of antenna system, here shown diagrammatically, has an an-

tenna tuning and loading arrangement J associated with it, this arrangement being connected to the movable element of another two-position switch J', this movable element being shown in receiving position in solid lines and in transmitting position in dotted lines. In this latter position the modulated and amplified carrier wave is delivered to the antenna and transmitted in conventional fashion.

When the system is switched from transmission to reception without touching the tuning control (as by operation of the ganged throw-over switches), the fixed frequency delivered by C and D is changed and receiving connections are made throughout the system. For example, the fixed oscillator used on transmission might have been generating one megacycle and the multiplier quadrupling this; the tunable oscillator may have been set at 1500 kilocycles; and the mixer might be arranged for subtracting, this being preferable, resulting in a transmitting frequency of 2500 kilocycles. When the change over was made to reception the fixed frequency generator might be changed so as to deliver 5 megacycles to the mixer B, the change in position of the switches F' and J' causing the displaced mixer wave output of 3500 kilocycles and any signals received on the antenna to be delivered to the receiving portion of the system.

The receiving portion of the system is shown schematically as comprising a radio frequency amplifier K; a mixer L having tuned circuits associated therewith; an intermediate frequency amplifier M, the tuned circuits of this amplifier being peaked at a frequency of one megacycle under the conditions assumed; a second detector N; and a conventional audio amplifier O. The 3500 kilocycle signal delivered to the mixer, in conjunction with the intermediate frequency amplifier circuit tuned to one megacycle, enables the receiving portion of the system to pass only a 2500 kilocycle signal or a 4500 kilocycle signal, any signals on this latter frequency being eliminated by the radio frequency tuned circuits. Accordingly, only signals on the 2500 kilocycle frequency, the same as that used on transmission, are delivered to the detector N and audio amplifier O. In order to achieve this desired result in the system here disclosed, the circuits of the intermediate frequency amplifier M must be tuned to the frequency representing the difference between adjacent steps or frequencies delivered by the fixed frequency generator here shown as comprising the fixed oscillator C and the multiplier D, although it will be understood that a plurality of independent fixed frequency oscillators could be used rather than a single oscillator and a multiplier.

For the purpose of this description, it will be assumed that the fixed oscillator C delivers a fixed frequency of one megacycle; and that the multiplier is arranged to multiply this 5, 6, 7 or 8 times; and that the tunable oscillator A is so designed as to have its frequency variable over a range from one megacycle to two megacycles. Operation of the change-over switch arrangement always displaces the output of the fixed frequency generator by one megacycle, preferably raising it one megacycle in each case regardless of its initial setting, the initial setting determining the band on which transmission and reception is effected. This results in always displacing the wave output of the mixer B by one megacycle upon the change-over from transmission to reception. In this regard it will be understood that the word "dis-

placement" is intended broadly to cover either an increase or a decrease of frequency. For convenience of description, the frequency used for transmission is being termed the "selected," "initial" or "desired" frequency, and the different frequency for local heterodyning purposes is being termed the "displaced" frequency.

Referring now more particularly to the circuit diagram of Figure 2 (comprising portions 2a and 2b), the portions corresponding to the various rectangles of the block diagram of Figure 1 are similarly lettered. The oscillator A is shown as comprising a tube 10, which may be tube type No. 6J5, having a tank circuit comprising a permeability tuned variable inductance 11 and a fixed condenser 12. While the tuned tank circuits throughout the system are shown as having fixed condensers (fixed except for such slight variations as may be desirable for trimming purposes) and variable inductances, it will be understood that the principle is equally applicable to circuits where the inductances are fixed and tuned by variable condensers. Moreover, as will be more apparent later on in the description, the various tank circuits switched in changing from one frequency band to another are shown as completely separate and independent tank circuits, whereas in practice it may be necessary only to switch the fixed elements of such circuits.

The output of the oscillator A is here shown as loosely coupled to the signal grid of the mixer B, here shown as comprising the tube 13, which may be tube type No. 6SA7, and its associated tuned circuits. The system here illustrated is shown as intended to provide transmission and reception on three bands, and the tuned circuits associated with the mixer tube during transmission are the three tank circuits comprising the tunable inductances 14a, 14b and 14c, together with fixed condensers 15a, 15b and 15c; and those used during reception comprise the variable inductances 16a, 16b and 16c, together with the fixed condensers 17a, 17b and 17c. Selection of the tank circuit appropriate to the particular band is effected by the band switch elements associated therewith, all such band switch portions throughout the set being ganged in accordance with conventional practice; and change over from transmission to reception is effected by the switch 18, part of the change-over relay.

The injection grid of the mixer tube 13 is supplied with any of a plurality of desired fixed frequencies from the fixed frequency generator comprising the portions C and D. The fixed oscillator C is here shown as comprising a tube 19, which may also be a tube type No. 6J5, having associated therewith a tank circuit, comprising the inductance 20 and the fixed condenser 21, and the crystal 22, the tank circuit and crystal holding the output of the oscillator tube 19 at a fixed predetermined frequency, as one megacycle. The output of this fixed oscillator is delivered to a multiplier here shown as comprising the tube 23, which may be tube type No. 6SJ7, and associated tuned circuits, certain of such circuits being used for transmission and other of said circuits for reception. Since the fixed frequency generator need only deliver four fixed frequencies for proper operation on three bands, only four tuned circuits are associated with the multiplier or distorter tube 23. Three-position band switch sections, forming part of the ganged band switch arrangement of a system, are coordinated with two-position switches forming part of the change-over relay arrangement to control selection of the circuits for trans-

mission and reception. These four tuned circuit arrangements are here identified in general as 24, 25, 26 and 27. Since they are all similar in arrangement, except for the specific values of the reactances used, only one will be described in more detail. The tuned circuit combination identified as 24, for example, comprises fixed inductances 24a and 24b, these being coupled through the fixed condensers 24c and 24d, these condensers each being in shunt with the respective inductances 24a and 24b through the fixed condenser 24e. When the band switch is set in the first band position, as shown in the drawings, the tuned arrangement 24 is used on transmission and the tuned arrangement 25 during reception (the transmission - reception change - over switches being shown in this latter position); on band 2, the tuned arrangement 25 is used on transmission and 26 during reception; and on band 3 the arrangement 26 is used for transmission and 27 for reception. It will be understood that this particular single-frequency fixed oscillator C and multiplier D are used for convenience, and for absolute accuracy of spacing between the frequencies on transmission and reception; but that a plurality of individually crystal controlled fixed oscillator arrangements could also be used. Also, while the reactance elements in the tank circuits associated with the tubes 19 and 23 are spoken of as "fixed," it will be understood that they are not tuned or varied during operation of the system; but that certain of such elements may be variable, or may have smaller, similar variable reactances in shunt or series therewith for trimming purposes.

The wave output of the mixer B is delivered to the buffer amplifier E comprising the tube 28, which may be tube type No. 6SJ7, and its associated tuned circuits here designated as the filter 40 circuits F. There are two sets of such tuned circuits, one for transmission and one for reception, the change over being by means of the change-over switch 29. The set of tuned circuits used on transmission are here identified as 30, 31 and 32; and the corresponding set used on corresponding bands for reception are here identified as 33, 34 and 35. Each tuned circuit is here shown as comprising a tuned inductance element (ganged with the other tuned elements throughout the system), and a fixed capacitive element. The output of the buffer amplifier and filter circuit in use at any particular time is adapted to be selectively connected, through operation of the change-over switch F', either to the first tube of 55 the power amplifier, or to the mixer or first detector in the super-heterodyne receiving system, this latter position of the switch being that shown in the drawings.

First to follow out circuits during transmission, 60 however, the output of the filter circuit F is then delivered through the switch F' (when it is in the position other than that shown) to the first tube of the power amplifier, which may be tube type No. 6SJ7, this tube being here identified as 36. Associated with the plate circuit of this tube are three tank circuits here identified as 37, 38 and 39, comprising variable inductances, also part of the ganged tuning arrangement, and fixed condensers. The output of this amplifying tube is here shown as delivered to a power amplifier tube 40, which may be tube type No. 807. The plate output of this tube is connected to the transmitting contact of the two-position change over switch 41. When this switch is in the transmit-

ting position (the position other than that shown) the output of the power amplifier is delivered to the antenna, the transmitted frequency being still further controlled by the tuned tank circuits here identified as 42, 43 and 44, these circuits also serving as the first or primary radio frequency circuits upon reception. All of the three-position switches are, of course, sections of a single band switch; and all of the two-position switches discussed are sections of the change-over relay.

Modulation is effected by the modulator arrangement G. This is here shown as a first amplifier tube 45 adapted to be controlled by a microphone, a key, or other conventional means. The amplified output of this tube is delivered, through a resistance coupling, to a power modulator tube 46, which may be tube type No. 807. The output of this modulator tube is transformer coupled to one of the grids of the power output tube 40 to effect the desired modulation. It will be understood that the various amplifying portions heretofore described, and those to be described in connection with the receiving portion of the system, are shown with the minimum number of tubes providing an operative arrangement, for purposes of simplicity of illustration. In commercial practice, most of these various amplifying sections would comprise a larger number of tubes. For example, the power output tube 40 would normally be preceded by more than one stage of preliminary amplification, and the same is true of the modulator tube 46; the multiplier would normally comprise at least two tubes, so that when higher orders of multiplication are desired one tube can double and the succeeding tube triple or quadruple, for example; and the radio frequency, intermediate frequency and audio frequency amplifying portions of the superheterodyne receiver portion of the system would usually comprise several tubes in cascade, rather than single tubes shown as representative.

Referring now more particularly to Figure 2a, the radio frequency amplifying portion K of the receiving system is here shown as comprising a tube 50, which may be tube type No. 6SK7, with its output tuned by one of the three tank circuits 51, 52 and 53, depending upon the band to which the set is tuned. The output of this radio frequency amplifier is here shown as delivered to the signal grid of the first detector or mixer tube 54, which may be tube type No. 6SA7; and the injection grid of this tube 54 is supplied with the displaced wave output from the mixer B, through the wire 55. Signals received on the antenna and which have passed the tuned circuits associated with the antenna and with the output of the tube 50 are thus beat down in the first detector tube 54, to an intermediate frequency, and this intermediate frequency is amplified in an intermediate frequency amplifier here shown as comprising only the tube 56. Input and output coupling associated with this tube 56 is through conventional tuned intermediate frequency amplifier coupling circuits here identified as 57 and 58; and in the circuit heretofore assumed these would be tuned to pass 1,000 kilocycles and only a few kilocycles on each side of this central or peak frequency. The output of the intermediate frequency amplifier is then delivered to a detector and first audio amplifier comprising the tube 59, which may be tube type No. 6SQ7. The output of this tube is here shown as delivered to a power or output audio amplifying stage here shown as including the tube 60, which may be tube type No. 6V6; and the output of this tube may be

transformer coupled to any desired translator, as earphones or a loud speaker.

If it be assumed, as heretofore, that the fixed oscillator C generates a wave of a frequency of one megacycle, that the tunable oscillator covers a band of from one to two megacycles, and that it is desired to have the three bands covered by the set 3-4, 4-5 and 5-6 megacycles, the values of the reactances in the various tuned circuits may be readily calculated by anyone skilled in the art. The values of inductances and capacities should be so chosen that the tuned circuits associated with the antenna, the radio frequency amplifier 50, and those in the power amplifier, should be such that they are tunable, respectively, from 3-4, 4-5, and 5-6 megacycles; and the tuned circuits associated during transmission with the mixer tube 13 and with the output of the buffer amplifier 28 should be similarly tunable over similar ranges. The tank circuits associated during reception with the output of the mixer 13 and with the output of the buffer amplifier 28 should be designed to tune over bands of 4-5, 5-6, and 6-7 megacycles, respectively. The circuits 24, 25, 26 and 27 forming part of the multiplier arrangement, would, under the conditions assumed, be tuned to 5, 6, 7 and 8 megacycles, respectively. Other circuit constants would be of conventional value for the particular tubes used, the present invention residing in a new concept and combination of circuit elements rather than in critical values of any particular elements of the combination.

I find it preferable to use subtraction rather than addition in achieving the desired outputs of the mixers 13 and 54, particularly the former, as this avoids trouble with harmonics of the fixed frequencies. In the case of the particular bands and frequencies assumed, however, where the tunable oscillator has a minimum frequency less than half that of the desired frequency, second, third and fourth harmonics of the frequency of this variable oscillator intersect or meet frequencies in the desired bands. I have found that difficulty in this regard can mostly be eliminated by the use of two sharply tuned circuits (preferably link coupled, as illustrated) between the variable oscillator 10 and the mixer 13.

Even if the mixer input derived from the variable oscillator very closely approximates a pure sine wave, however, the mixing action in the mixer 13 inherently creates harmonics, so that no amount of care in the use of sharply tuned circuits between the variable oscillator and the mixer can completely eliminate such trouble; and tuned circuits subsequent to the mixer are of little value in eliminating the harmonic interference, since if the undesired harmonic wave approaches the desired signal frequency, the harmonic wave goes through the subsequent tuned circuits with little attenuation.

The output of a mixer following the square law, as is the general case, has a desired output proportional to the product of the two input voltages; the second harmonics are proportional to the square of the voltage with which it is associated (although with a different constant factor, of course); and the succeeding harmonic is approximately proportional to the cube of the voltage from which it is derived. If the frequency derived from the fixed frequency generator is above the desired frequency in which the operator is interested, as is preferably the case, its voltage may be made quite strong with no trouble from its harmonics, as they are always above the

band of frequencies in which the operator is interested. On the other hand, since the desired signal output is proportional to the product of the two voltages delivered to the mixer, reduction in strength of the voltage of the variable oscillator only reduces the value of the desired signal as a direct function while reducing the value of the second harmonic as a square function, of the third as a cube function, etc.

Accordingly, where the fixed frequency is above the desired signal frequency and the tunable frequency below it, as I have found to be preferable, difficulty with harmonics of the variable oscillator frequency can be minimized by making the variable oscillator voltage delivered to the mixer very small, and that delivered from the fixed oscillator many times greater, preferably one hundred or more times greater than the voltage of the variable oscillator. In a particular model of this system which I have built, I have found it desirable to so arrange the couplings and powers of the fixed and variable oscillators that one of the grids of the mixer 13 has about two volts delivered to it from the fixed oscillator, while the other grid has a voltage delivered to it from the tunable oscillator which is in the order of $1/100$ of a volt. This results in the second harmonic of the tunable oscillator voltage being about 70 decibels down in the plate current of the mixer tube with other harmonics being proportionately lower. Even where the second harmonic frequency is exactly the same as the desired frequency, therefore, as happens at two or three places in the bands previously described, such second harmonic voltage is sufficiently minimized that, as a practical proposition, it does not create objectionable interference; and where the desired and harmonic frequencies differ even slightly, the subsequent tuned circuits associated with the buffer and power amplifier attenuate the undesired signal even further.

One every considerable advantage of spacing the various fixed frequencies by ten-to-an-integral-power cycles (as one megacycle) is that it enables the use of an improved direct reading frequency indicating arrangement enabling direct reading of the frequency at any setting on any of the bands. Moreover, having the variable oscillator cover the same range under all circumstances and deriving the desired output in the different bands by mixing different fixed frequencies therewith results in the same frequency spread, and exactly similar tuning characteristics in each of the various bands. Moreover, combining the tunable oscillator wave with a crystal controlled, fixed frequency wave several times its frequency proportionately reduces the percentage of frequency drift which may be present in the output of the variable oscillator. The combined results provide a radio system with very desirable tuning characteristics.

The way in which the frequency to which the system is tuned may be read from the indicating means (within the limits of accuracy of the calibration, of course) is apparent from Figure 3. One indicating member, here identified as 70, is connected to and actuated by and in accordance with the band switch; and this indicating arrangement, in each particular position, shows only a single digit corresponding to the initial digit of the band frequency. That is, in the band frequencies previously assumed, the indicator 70 would exhibit the numeral 3 when the band switch was in its first position; and the numerals 4 and 5 would be exhibited, respectively, when

the band switch was in its second and third positions.

The indicating arrangement associated with the variable reactive element of the tunable oscillator (the variable inductance in this particular case) is here identified as 71. This may be a steel tape, as illustrated, or a dial or a cylinder; and it is arranged adjacent and readably following the other indicator, in the particular case illustrated being immediately beneath the other indicator. Moreover, the second indicator 71 should bear such numerals, preferably vertically arranged as illustrated, as are necessary to complete the frequency reading in kilocycles. In the particular example illustrated in Figure 3, the set is on the second band, covering 4-5 megacycles; and the setting of the variable element of the tunable oscillator is such that the desired frequency is near the lower end of this band, 4150 kilocycles; and this is directly and conveniently readable from the indicator arrangement. If the band switch is changed to the first band without varying the setting of the tunable oscillator, the indicating arrangement would immediately show that the frequency to which the set is tuned is 3150 kilocycles; whereas if the band switch had been left in the second band and the tunable oscillator control changed until its frequency was exactly in the middle of the band, the indicator would immediately show that the frequency to which the set is tuned is 4500 kilocycles. It is obvious that such a desirable indicating arrangement can be used at any time that the variable tuning covers the same range in each band, such range is 100, 1000, 1,000,000 or any number of cycles which is ten-to-an-integral-power cycles, and wherein the band switch arrangement provides steps which are each some multiple of this number. That is, if the tunable oscillator were to cover only a range of 100 kilocycles, the same desirable direct reading could be achieved by having the band switch effect band changes which are some multiples of 100. In such a case, of course, the band switch indicator would still provide the first digit but the second indicator arrangement would only provide two succeeding digits.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Radio apparatus of the character described, including: a variable frequency generator; a fixed frequency generator; means for mixing the outputs of said generators and filtering the resultant waves to provide an initial wave output; means for amplifying and transmitting said initial wave output; means for displacing the frequency of the fixed generator to effect a predetermined displacement of the frequency of the wave output; and a super-heterodyne receiving system having an intermediate frequency amplifier adapted to pass a frequency corresponding to the difference between the initial and displaced frequencies of said waves, a mixer delivering its output to the intermediate frequency amplifier, and means for connecting the first mentioned mixer to the last mentioned mixer, whereby the displaced waves serve as the local heterodyning waves for said receiving system.

2. Radio apparatus of the character described, including: a variable frequency generator; a fixed frequency generator; means for mixing the outputs of said generators and filtering the resultant waves to provide an initial wave output; means for amplifying and transmitting said initial wave output; means for displacing the frequency of the fixed generator by a given frequency to effect a displacement of the frequency of the wave output by said given frequency; and a super-heterodyne receiving system having an intermediate frequency amplifier tuned to said given frequency, a mixer delivering its output to the intermediate frequency amplifier, and means for connecting the first mentioned mixer to the last mentioned mixer, whereby the displaced waves serve as the local heterodyning waves for said receiving system.

3. Apparatus of the character claimed in claim 2, wherein the variable generator is tunable over a band having a width equal to said given frequency.

4. Radio apparatus of the character described, including: a variable frequency generator; a fixed frequency generator; means for mixing the outputs of said generators and filtering the resultant waves to provide an initial wave output; means for amplifying and transmitting said initial wave output; means for displacing the frequency of the fixed generator by a given frequency to effect a displacement of the frequency of the wave output by said given frequency; a super-heterodyne receiving system having an intermediate frequency amplifier tuned to said given frequency and a mixer delivering its output to the intermediate frequency amplifier; and selectively operable means for connecting the mixer to the amplifying means in one operative position and for actuating the displacing means and connecting the first mentioned mixer to the mixer of the receiving system in another operative position, whereby the displaced waves serve as the local heterodyning waves for said receiving system and the received frequency is identical with the transmitted frequency.

5. Apparatus of the character claimed in claim 1, wherein the mixer subtracts the frequency of the variable generator from that of the fixed generator to provide said initial wave output.

6. Apparatus of the character claimed in claim 4, wherein the mixer subtracts the frequency of the variable generator from that of the fixed generator to provide said initial wave output.

7. Apparatus of the character claimed in claim 1, wherein the voltage delivered to the mixer from the fixed generator is many times that delivered from the variable generator and the mixer subtracts the frequency of the variable generator

from that of the fixed generator to provide said initial wave output.

8. Radio apparatus of the character described, including: a fixed frequency generator adapted to selectively provide a plurality of waves of frequencies differing by a given frequency; a variable frequency generator tunable over a band having a width equal to said given frequency; means for mixing the outputs of said generators and filtering the resultant waves to provide an initial wave output; means for amplifying and transmitting said initial wave output; means for selecting another of said plurality of fixed frequencies to effect a displacement of the frequency of the wave output by said given frequency; and a super-heterodyne receiving system having an intermediate frequency amplifier tuned to said given frequency, a mixer delivering its output to the intermediate frequency amplifier, and means for connecting the first mentioned mixer to the last mentioned mixer, whereby the displaced waves serve as the local heterodyning waves for said receiving system.

9. Apparatus of the character claimed in claim 8, wherein said given frequency is ten-to-an-integral-power cycles.

Certificate of Correction

Patent No. 2,457,134.

December 28, 1948.

MELVIN L. DOELZ

It is hereby certified that error appears in the printed specification of the above numbered patent requiring correction as follows:

Column 1, line 36, for the word "combination" read *communication*;
and that the said Letters Patent should be read with this correction therein that the same may conform to the record of the case in the Patent Office.

Signed and sealed this 24th day of May, A. D. 1949.

[~~SEAL~~]

THOMAS F. MURPHY,
Assistant Commissioner of Patents.
